(57) **CLAIM**

The ornamental design for an electric brush, as shown and described.

DESCRIPTION

FIG. 1 is a front, right perspective view of an electric brush showing my new design.

FIG. 2 is a rear, left perspective view thereof.

FIG. 3 is a front view thereof.

FIG. 4 is a rear view thereof.

FIG. 5 is a left side view thereof.

FIG. 6 is a right side view thereof.

FIG. 7 is a top enlarged view thereof.

FIG. 8 is a bottom enlarged view thereof.

FIG. 9 is an enlarged detail view of area 9 shown in FIG. 1.

FIG. 10 is an enlarged detail view of area 10 shown in FIG. 1; and,

FIG. 11 is an enlarged detail view of area 11 shown in FIG. 2.

The short evenly dashed broken lines shown in the figures illustrate portions of the electric brush that form no part of the claimed design. The short-dash long-dash broken lines in FIGS. 1 and 2 show the boundaries for the enlarged view shown in FIGS. 9-11 and form no part of the claimed design.
